[57] CLAIM

The ornamental design for a utility blower, as shown and described.

DESCRIPTION

FIG. 1 is a top plan view of a utility blower showing our new design;

FIG. 2 is a front elevational view thereof;

FIG. 3 is a bottom plan view thereof;

FIG. 4 is a left side elevational view thereof rotated

counterclockwise 90°;

FIG. 5 is a right side elevational view thereof rotated

clockwise 90°; and,

FIG. 6 is a rear elevational view thereof.

The solid black surface shading shown in FIGS. 1-6 is

understood to represent openings.
